UNITED STATES PATENT OFFICE.

HERMAN IHLENBURG, OF PHILADELPHIA, PENNSYLVANIA, ASSIGNOR TO
DAVID WOLFE BRUCE, OF NEW YORK, N. Y.

DESIGN FOR TYPE.

SPECIFICATION forming part of Design No. 15,751, dated January 27, 1885.

Application filed December 13, 1884. Term of patent 14 years.

To all whom it may concern:

Be it known that I, HERMAN IHLENBURG, (assignor to DAVID WOLFE BRUCE,) of the city and county of Philadelphia, Pennsylvania, 5 have invented a new Design for a Font of Printing-Type, of which the following is a specification.

The nature of my design is clearly shown in the accompanying typographic impression, to 10 which reference is made; and it consists of a script letter of the running-hand character, ornamented by the flourishes extended below the line, as shown. The B, D, H, K, M, N, R, U, V, W, X, and Y are further ornamented 15 by the inclined line, with dot termination extending upon the left from the upper portion

of the up and down portion of the letter. The cross-line of the A is provided upon the left with the dot termination.

The character of the design is preserved in 20 the lower-case, the punctuation-marks, the numerals, and the dollar and pound-sterling symbols, save that the flourishes are omitted, except in the latter.

I claim as new—

25 The design for a font of printing-type, as shown and described.

HERMAN IHLENBURG.
